UNITED STATES PATENT OFFICE.

JOSEPH H. MARGERISON, OF PHILADELPHIA, PENNSYLVANIA.

LOOM FOR WEAVING TERRY FABRICS.

SPECIFICATION forming part of Letters Patent No. 770,689, dated September 20, 1904.

Application filed March 25, 1903. Serial No. 149,545. (No model.)

To all whom it may concern:

Be it known that I, JOSEPH H. MARGERISON, a citizen of the United States, residing in Philadelphia, Pennsylvania, have invented Improvements in Looms for Weaving Terry Fabrics, of which the following is a specification.

My invention relates to that class of looms which are employed for weaving looped-pile or terry fabrics, the object of my invention being to so construct such a loom that it is available for the production of fabric in which looped-pile or terry portions alternate with closely-woven webs having a jacquard pattern or figure. This object I attain in the manner hereinafter set forth, reference being had to the accompanying drawings, in which—

Figure 1 is a view, partly in side elevation and partly in section, of sufficient of a loom to illustrate my present invention, the ordinary mechanism of the loom being shown by dotted lines and the parts to which my invention relates being shown by full lines. Fig. 1^a is a side elevation of the jacquard mechanism of the loom. Figs. 2 and 3 are face views of heddle-operating cams employed in connection with the loom. Fig. 4 is a similar view of the cam for operating the terry-motion. Fig. 5 is a view of part of the cam-shaft of the loom with said heddle-cams mounted thereon, together with certain supplementary cams preferably employed in connection therewith. Figs. 6 and 7 are face views, on a reduced scale, of said supplementary cams. Fig. 8 is a plan view of three pairs of cams and of certain mechanism co-operating therewith. Fig. 9 is a view illustrating a special embodiment of one of the features of the invention, and Fig. 10 is a view illustrating a modification of one feature of the invention.

In Fig. 1 of the drawings, 1 represents the cam-shaft of the loom; 2, the drop-box lever; 3, the drop-box rod, and 4 and 5 a pair of heddles suspended from levers 4^a and 5^a, respectively, these levers having depending rods or bars 4^b and 5^b, which are acted upon by cams on the shaft 1 so as to impart the desired rising-and-falling movement to the heddles 4 and 5, one of the same being raised as the other is lowered. These heddles con-

trol the ground warp-threads of the fabric, which are drawn from a warp-beam 6, the terry warp-threads being drawn from a warp-beam 7 and being controlled by harness-cords 8, which lead to a jacquard-machine, such as 55 described hereinafter. Other jacquard harness-cords 9 are adapted to control the ground warp-threads, and that portion of the jacquard-machine which controls these harness-cords 9 should be so constructed as to be rendered 60 operative or inoperative at will—as, for instance, by pushing out of engagement with the operating-lever 9^a, Fig. 1^a, the link 9^b, which normally connects said lever to the griff-frame for operating the lifters which are connected 65 to the harness-cords 9—this result being effected without stopping the operation of the griff-frame, which controls the harness-cords 8, and which therefore operates continuously. If both ground warp-threads and terry warp 70 threads are engaged both by heddles and by harness-cords, the jacquard-machine may have but one griff-frame, which is rendered inoperative when the heddles are in action and operative when the heddles are out of action. 75 Such a jacquard-machine is shown in Fig. 10. The heddles 4 and 5 have elongated eyes 10, so that while they serve to lift the ground warp-threads from the bottom to the top of the shed they will not when both depressed 80 offer any obstacle to the raising of the ground warp-threads by the harness-cords 9. In some cases it may be advisable to carry out this feature of my invention in the manner shown in Fig. 9—that is to say, by suspending from 85 the levers 4^a 5^a rods or bars 4^c 5^c, which engage with loops or elongated eyes 10^a in the harness-cords 9—so that while the latter will be lifted by the levers 4^a 5^a they can also be lifted independently thereof when under control 90 of the jacquard-machine, the cords 9 thus serving the double function of harness and heddles. While terry fabric is being woven, the ground warp-threads are controlled by the heddles, the harness-cords 9 being inoperative; but when it is desired to produce a closely-woven border or other portion of the web having a jacquard pattern or figure thereon the heddles are put out of operation and the ground warp-threads as well as the terry-threads are 100

controlled by the jacquard. The object of controlling the terry warp-threads at all times by means of the jacquard is because it is advisable to raise said terry warp-threads to a higher point than the ground warp-threads in forming the shed, although this result might of course be effected even if the terry warp-threads were controlled by heddles during the production of terry fabric by so operating 10 said terry warp-heddles that they would have a greater lift than the ground warp-heddles. By using heddles to operate the ground warp-threads during the production of terry fabric the cutting of the cards is simplified as 15 compared with those of a loom in which both the ground warp-threads and the terry warp-threads are shedded solely by the jacquard-machine during the weaving of both plain and terry fabric. In order to render the heddles 20 operative or inoperative at will, I use cams of the character which I will now proceed to describe, these cams being provided with switches, which are shifted from one position to another at such time as is necessary to 25 change the character of the fabric which is being woven. This shifting of the switches can be effected by the jacquard-machine or other element of the loom which is under the necessary control; but I preferably accomplish it by means of the drop-box mechanism of the loom in the manner hereinafter described.

Each of the heddle-lever bars 4^b and 5^b has an antifriction-roller 11, and each of the heddle-operating cams 12 and 13 has a low concentric portion 14, a high concentric portion 15, and intervening movable switches 16 and 17 bridging the space between the low concentric portion of the cam and the high concentric portion of the same. These pivoted switches are normally held in operative position by coiled springs 18, "operative position" meaning that position of the switches shown by full lines in Figs. 2 and 3 and which causes 40 reciprocation of the heddle-lever bars. The spring 18 of the switch 16 acts directly upon a pin projecting from said switch through a segmental slot in the cam, but the spring 18 of the switch 17 acts upon an arm 19, secured 45 to the pivot-pin of the switch on the outside of the cam, said arm carrying on its outer end an antifriction-roller 20. Adjacent to the periphery of each of the cams 12 and 13 is a shoe 21, hung to the outer end of an arm 22, which is secured to a rock-shaft 23, having 50 another arm, 24, provided with antifriction-roller, which engages a grooved cam 25, suitably mounted upon a stud, shaft, or spindle 26, and having an arm 27 connected by a link 55 28 to the drop-box lever 2, as shown in Fig. 1. During the weaving of terry fabric one of the extreme boxes of the set—in the present instance the top box—is in action and remains in action, and under these circumstances 60 65 the cam 25 so acts upon the arm 24 that each

shoe 21 will be held away from the path traversed by the antifriction-rollers 20 of the switch-arms of the two cams. Hence both cams will remain operative and the heddles 4 and 5 will be properly shedded. When it is desired to change the character of the weave, however, the drop-box rod is raised so as to bring the other boxes into action, and this movement effects corresponding movement of the cam 25 and throws each shoe 21 into position to engage with the antifriction-roller on the switch-arm of its corresponding cam 12 or 13, the effect of which is to move the switches 17 to the position shown by dotted lines in Figs. 2 and 3, so that the antifriction-roller 11 on each of the heddle-lever bars now traverses continuously in contact with the low concentric portion of each cam, tripping the switch 16 on each rotation of the cam. This has the effect of rendering the heddles inoperative, and by suitable connection between the drop-box lever 2 and the jacquard-machine the harness 9 may at the same time be rendered operative so that all of the warp-threads, both ground and terry, now become harness-operated and a closely-woven jacquard pattern or figure can be produced, it being understood, of course, that the movement of the lay of the loom is at the same time changed from the differential beat employed in weaving the terry fabric to the uniform beat necessary in weaving the close fabric. This can be effected by means similar to those employed for rendering the heddle-cams operative or inoperative—that is to say, one of the switches 30 with which the terry-motion cam 31 is provided may have an arm 32 to be actuated by connection with some part of the drop-box mechanism when the same is raised, or by a shoe 33 on an arm 34 of the rock-shaft 23 (see Fig. 8) at the same time that the switches 17 of the cams 12 and 13 are being operated by the shoes 21, or, if desired, the switches of all three of the cams 12, 13, and 31 may be operated by one and the same shoe, if the latter is of proper width. The terry-motion cam acts to shift forward and backward the boxes carrying the crank-shaft which effects vibration of the lay, the latter having a full beat when the boxes are 100 in the forward position and only a partial beat when the boxes are in the retracted position. In the present instance each bearing-box is shown by dotted lines in Fig. 1 connected to one arm of a bell-crank lever 50, whose other arm is connected to a lever 51, the latter being connected to a bar 52, which is acted upon by the terry-motion cam. This bar has an antifriction-roller 53, and when the roller is acted upon by the high part of the cam 31, as shown in Fig. 4, the bearing-boxes of the crank-shaft are retracted; but when the roller is traveling in contact with the low part of the cam said bearing-boxes are projected. When the switch 30 is open, 105 110 115 120 125 130

the roller 53 travels continuously in contact with the low portion of the cam. Consequently the bearing-boxes are projected and the lay has a full beat on every pick. The throwing 5 into operation of that part of the jacquard-machine which controls the harness-cords 9 may also be effected by the described movement of the drop-box lever, the latter being connected by a cord 35 to a cam 36, which 10 acts upon the link 9^b to throw it out of engagement with the operating-lever, a spring 37 acting upon said cam to move it in opposition to the pull of the cord 35, or the hooks which control the harness-cords 9 may be held 15 out of operation by a suitable formation of the pattern-cards during the weaving of terry fabric and permitted to come into operation by a change in the character of the cards when necessary. As the cam 31 will usually be 20 driven at a rate of speed different from that of the cams 12 and 13, said cam is mounted on a sleeve 38 on the shaft 1 and is driven from the main shaft by a train of gears 40, 41, and 42, different from the gears 43, 44, 25 and 45, which drive the shaft 1, these gears being represented by the dotted circles in Fig. 1. The cam 25 is so formed that as long as any of the boxes other than the top box are 30 in action the shoes 21 and 33 will be maintained in such position as to move the switches 17 and 30 to the position shown by dotted lines in Figs. 2, 3, and 4 on each rotation of each cam 12, 13, or 31; but as soon as the 35 weaving of close fabric has been completed and the top box has again been brought into action the shoes will be withdrawn and the switches permitted to assume and retain their normal position, as shown by full lines, so as to again render operative the heddles 4 and 5, 40 and at the time the harness 9 is put out of action and the lay resumes its differential beat.

In connection with each of the cams 12, 13, and 31 I prefer to use a supplementary cam 45 12^a, 13^a, or 31^a, which is in the nature of a dummy cam, having portions 14^a and 15^a parallel with the low and high concentric portions of the corresponding cams 12, 13, or 31, but having nothing corresponding with the 50 switches 16, 17, or 30, so that it does not interfere with the free movement of the anti-friction-rollers over or under said switches. These dummy cams act upon supplementary antifriction-rollers 11^a, as shown in Fig. 4.

55 While I prefer to effect automatically, as described, the various operations necessary to change from the weaving of terry fabric to the weaving of close fabric with pattern or figure thereon, my invention, in its broader embodiment, is not limited to such automatic operation, but contemplates as well the making of the necessary changes by hand.

Having thus described my invention, I claim and desire to secure by Letters Patent—

65 1. The combination in a loom for weaving

terry fabrics, of heddles and harness, each adapted to control warp-threads, and means for rendering the harness inoperative during the period of heddle control, substantially as specified.

2. The combination in a loom for weaving 70 terry fabrics, of heddles and harness, each adapted to control warp-threads, and means for rendering the heddles inoperative during the period of harness control, substantially as specified.

3. The combination in a loom for weaving 75 terry fabrics, of heddles and harness, each adapted to control the ground warp-threads, and harness controlling the terry warp-threads, substantially as specified.

4. The combination in a loom for weaving 80 terry fabrics, of heddles and harness, each adapted to control the ground warp-threads, harness controlling the terry warp-threads, 85 and means for rendering the ground-warp-thread heddles inoperative during the time that said threads are harness-controlled, substantially as specified.

5. The combination in a loom for weaving 90 terry fabrics, of heddles and harness, each adapted to control the ground warp-threads, harness controlling the terry warp-threads, and means for rendering the ground-warp-thread harness inoperative during the time 95 that said ground warp-threads are heddle-controlled, substantially as specified.

6. The combination in a loom for weaving 100 terry fabrics, of harness and heddle mechanism, and means for rendering said heddle mechanism inoperative during the period of harness control, one of said mechanisms having elongated eyes whereby operation of either may be effected without interference by the other, substantially as specified.

7. The combination in a loom for weaving 105 terry fabrics, of harness and heddles, each adapted to control warp-threads, and means for rendering the heddles inoperative during the period of harness control, said heddles 110 having elongated eyes or loops for the passage of the warp-threads, whereby they will not interfere with the movement of said warp-threads by the harness, substantially as specified.

8. The combination in a loom for weaving 115 terry fabrics, of heddles and harness, each adapted to control warp-threads, and means connected to some moving part of the loom for rendering the heddles inoperative during 120 the period of harness control, substantially as specified.

9. The combination in a loom for weaving 125 terry fabrics, of heddles and harness, each adapted to control warp-threads, and means connected to the drop-box mechanism for rendering the heddles inoperative during the period of harness control, substantially as specified.

10. The combination in a loom for weaving 130

- terry fabrics, of heddles and harness, each adapted to control warp-threads, and means connected to some moving part of the loom for rendering the harness inoperative during 5 the period of heddle control, substantially as specified.
11. The combination in a loom for weaving terry fabrics, of heddles and harness, each adapted to control warp-threads, and means 10 connected to the drop-box mechanism for rendering the harness inoperative during the period of heddle control, substantially as specified.
12. The combination in a loom for weaving 15 terry fabrics, of heddles and harness, each adapted to control the ground warp-threads, harness controlling the terry warp-threads, and means connected to some moving part of the loom for rendering the heddles inoperative 20 during the time that the ground warp-threads are harness-controlled, substantially as specified.
13. The combination in a loom for weaving 25 terry fabrics, of harness and heddles, each adapted to control the ground warp-threads, harness controlling the terry warp-threads, and means connected to the drop-box mechanism for rendering the heddles inoperative during the time that the ground warp-threads 30 are harness-controlled, substantially as specified.
14. The combination in a loom for weaving 35 terry fabrics, of heddles and harness, each adapted to control the ground warp-threads, harness controlling the terry warp-threads, and means connected to some moving part of the loom for rendering the ground-warp-thread harness inoperative during the time that said ground warp-threads are heddle-controlled, substantially as specified.
15. The combination in a loom for weaving 40 terry fabrics, of harness and heddles, each adapted to control the ground warp-threads, harness controlling the terry warp-threads, and means connected to the drop-box mechanism for rendering the ground-warp-thread harness inoperative during the time that said ground warp-threads are heddle-controlled, substantially as specified.
16. The combination in a loom for weaving 45 terry fabrics, of harness for controlling the ground and terry warp-threads, and means for throwing out of action, at intervals, the terry-motion for operating the lay, so as to provide for a full beat of the latter, substantially as specified.
17. The combination in a loom for weaving 50 terry fabrics, of harness for controlling both the ground and terry warp-threads and means connected to some moving part of the loom for throwing out of action, at intervals, the terry-motion which controls the movement of the lay, substantially as specified.
18. The combination in a loom for weaving 55 terry fabrics, of harness controlling both the ground and terry warp-threads, and means connected to the drop-box mechanism for throwing out of action, at intervals, the terry-motion which controls the movement of the lay, substantially as specified.
19. The combination in a loom for weaving 60 terry fabrics, of a cam having a movable switch whereby it is rendered operative or inoperative, and means for moving said switch to operative or inoperative position, said means being under control of the drop-box mechanism of the loom, substantially as specified.
20. The combination in a loom for weaving 65 terry fabrics, of a cam having a movable switch, a shoe for operating the same, a cam for controlling the position of said shoe, and a connection between said cam and some moving part of the loom, substantially as specified.
21. The combination in a loom for weaving 70 terry fabrics, of a cam having a movable switch, a shoe for operating the same, a cam for controlling the position of said shoe, and a connection between said cam and the drop-box lever, substantially as specified.
22. The combination in a loom, of a jacquard lifter-frame, mechanism for effecting vertical reciprocation of the same, and means whereby said mechanism is rendered operative or inoperative by connection with the drop-box 75 mechanism of the loom.
